(57) **CLAIM**

The ornamental design for a beverage container as shown
and described.

DESCRIPTION

FIG. 1 is a top perspective view of a beverage container
showing our new design.

FIG. 2 is a bottom perspective view thereof.

FIG. 3 is a left side elevational view thereof.

FIG. 4 is a rear elevational view thereof.

FIG. 5 is a front elevational view thereof.

FIG. 6 is a right side elevational view thereof.

FIG. 7 is a top plan view thereof.

FIG. 8 is a bottom plan view thereof.

FIG. 9 is a top perspective view of a second embodiment
thereof.

FIG. 10 is a bottom perspective view thereof.

FIG. 11 is a left side elevational view thereof.

FIG. 12 is a rear elevational view thereof.

FIG. 13 is a front elevational view thereof.

FIG. 14 is a right side elevational view thereof.

FIG. 15 is a top plan view thereof; and,

FIG. 16 is a bottom plan view thereof.

The broken lines depict portions of the beverage container
that form no part of the claimed design.

1 Claim, 14 Drawing Sheets
